UNITED STATES PATENT OFFICE.

JOHN P. CULVER, OF LOS ANGELES, CALIFORNIA.

ASPHALT-COATED SHEET-METAL PIPE.

SPECIFICATION forming part of Letters Patent No. 400,832, dated April 2, 1889.

Application filed December 14, 1888. Serial No. 293,584. (No model.)

To all whom it may concern:

Be it known that I, JOHN P. CULVER, a citizen of the United States, residing at Los Angeles, in the county of Los Angeles and 5 State of California, have invented a new and useful Riveted Multiple Asphalted Sheet-Metal Pipe, of which the following is a specification.

My invention relates to improvements in 10 that class of pipe composed of a thin sheet of iron or other suitable metal wrapped upon itself and having a coating of asphaltum or other suitable cementing and protecting substance interposed between the layers of the 15 sheet metal.

It is desirable in pipe of this class that the 20 sections be made of a greater length than can be readily and cheaply riveted; and my invention relates more particularly to the riveting of the free edge of the sheet along the portions of the pipe which cannot be readily reached from the ends in riveting. It is also 25 desirable that such pipe be made of a slightly greater diameter at one end than at the other, so that the several joints may be fitted into each other.

One object of my invention is to produce a 30 strong, light, durable, and cheap pipe suitable for water, gas, and sewer pipes.

A further object is to provide cheap and 35 efficient means for securing the free edges of convolute sheet-metal pipes.

My invention consists of a pipe comprising 40 a convolute sheet of metal coated throughout its entire extent with asphaltum or other protective cementing substance, and having its free edge secured wholly or in part by means of rivets passing through the several thicknesses of metal and cementing substance.

It consists more particularly of such pipe 45 having the free edge of the sheet secured by rivets of metal cast within the rivet-holes and suitable molds for forming the heads of the rivets.

The drawings illustrate my invention and 50 the device for casting the rivets.

Figure 1 is a view of a section of pipe showing 55 the convolute sheet of metal secured by rivets. Fig. 2 is a longitudinal section through the line of rivets. The thickness of the sheet

and the asphaltum are exaggerated. This view also shows a portion of the mandrel within the pipe. It also shows a molding-cup set on the top of the pipe to form the set-head of the rivet to be cast.

In manufacturing the pipe the sheet of metal A, coated with asphaltum or other suitable cementing and protecting substance and wrapped convolute upon itself, is placed upon a mandrel, B, provided upon its upper side 60 with a hole, C, through which the punch-chip may pass down through the mandrel. A die-plate, D, is fitted into the mandrel. This die-plate is interchangeable, so that new die-plates may be substituted for worn ones. 65 Another hole, E, is provided in the top of the mandrel at the distance from the hole C corresponding to the space desired between the rivets. This hole is larger in cross-section than the cross-section of the rivet desired and 70 is intended to form a mold for the inner head of the rivet. G are the rivets.

H is the mold-cup for forming the outer or set head of the rivet.

When the sheet of metal is properly wrapped 75 and pressed firmly together, it will maintain its shape and sustain great pressure without being riveted; but when roughly handled, or when subjected to heat, the outer lap or edge of the sheet is liable to become loosened. The 80 object of the rivets is to hold the edge of the sheet in place. The bursting-strain upon the pipe is largely sustained by the fold of the sheet, so that the fastening for the edge of the sheet need not be very strong.

When the pipe has been made as above 85 described, I place the pipe upon the mandrel so that the punch-hole C will be under the point desired for the middle rivet, and a hole is punched with a proper die. Then the pipe 90 is drawn off of the mandrel until the rivet-hole punched centers with the hole E. Then the mold-cup H is fitted over the rivet-hole and molten metal is poured therein, thus forming a rivet. The next hole is then punched, 95 and the operation just described is continued until the rivets are set to the end of the pipe. Then the pipe is reversed and the rivets cast in the other end in the same manner. If desired, ordinary rivets may be placed at the 100

ends of the pipes in the manner now in common use. I have discovered that rivets formed of easily-fusible metal—such as alloys of zinc and lead, &c.—are sufficiently strong enough 5 for this purpose. By this means I am enabled to rivet the pipe throughout its entire length at a very slight expense. If desired, two or more rows of rivets may be used. The hole E in the mandrel and the hole J in the mold- 10 cup H form suitable molds for the heads of the rivets. L represents the asphaltum or other cementing substance. By this construction of pipe very thin iron can be used with two or more laps, thus making a strong pipe 15 thin enough to allow the ends to be fitted into each other, thus dispensing with the collars ordinarily used to form the joints.

Now, having described my invention, what I

claim as new, and desire to secure by Letters Patent, is—

1. A pipe comprising a convolute sheet of metal coated with a cementing substance and having its free edge secured by rivets passing through the several layers of metal and cementing substance.

2. A pipe comprising a convolute sheet of metal coated throughout its entire length with a protective cement, and provided with rivet-holes therein, passing through the free edge and the several layers of the metal and cement, and rivets of metal cast within the rivet-holes, as described.

JOHN P. CULVER.
